UNITED STATES PATENT OFFICE.

EDGAR MOSHER NORTH, OF BROOKLYN, NEW YORK.

CUT-OUT FOR ELECTRIC CIRCUITS.

SPECIFICATION forming part of Letters Patent No. 742,895, dated November 3, 1903.

Application filed January 21, 1903. Serial No. 140,047. (No model.)

To all whom it may concern:

Be it known that I, EDGAR MOSHER NORTH, a citizen of the United States, residing at Brooklyn, in the county of Kings and State 5 of New York, have invented certain new and useful Improvements in Cut-Outs for Electric Circuits, of which the following is a specification.

The object of this invention is to provide a 10 cheap, simple, and efficient automatic cut-out for electric circuits; and it consists of a pair of bars joined together slightly out of alinement with each other and connected at the joint with a link at right angles thereto, said link being 15 connected with a lever, the opposite end of this lever being in contact with the binding-post of a resistance-coil. The aforesaid bars, together with the link and lever, form the conductors for the current, and when same 20 becomes excessive the jointed bars are heated up, thus expanding them and throwing the circuit into a resistance-coil and cutting the said bars out of the circuit, all of which will now be set forth in detail.

25 In the drawings, Figure 1 is a top or plan view of the cut-out apparatus, showing the normal relation of the parts; Fig. 2, an edge view of the same, and Fig. 3 a cross-section on line 3 of Fig. 1.

30 In constructing the apparatus I provide a base 4, of insulating material, at each end of which is a binding-post. The binding-post 5 at one end is attached to a metal plate 6, to which plate also is hinged one end of a bar 35 7. At the other end of the base 4 is a binding-post 8, secured to an insulated plate 9, and below this plate is another plate 10, to which the end of a bar 11 is hinged, this bar being similar to bar 7 and jointed thereto at 12 and 40 in such a position that normally these bars are slightly out of alinement with each other.

Below the bar 7 and parallel therewith is a lever 13, hinged at one end to a post 14 and having its produced end 15 connected with 45 the jointed bars 7 11 at their hinged point 12 by means of a link 16. Beyond this link the end 15 is bent downwardly or toward the base 4 and is in contact with two plates 17 18, the former of which is in permanent electrical 50 connection with the plate 6 by means of a wire 19, and the latter plate 18 having a permanent electrical connection with the plate

10 by means of a wire 20. These contact-plates 17 18 are slightly separated from each other, as shown, so there is no connection 55 electrically between the conductors 19 20.

The free end of the lever 13 has a contact-face 21, which travels over the contact-posts 22 of the resistance-coil 23. When the apparatus is in its normal position, as shown 60 in Fig. 1, the contact-face 21 is in engagement with a plate 25, which is connected up with the plate 9 by means of a conductor 26. It will thus be seen that normally the current enters at the binding-post 5 and trav- 65 erses the bars 7 11, plate 10, conductor 20, plate 18, lever 15 13, plate 25, and conductor 26 to the binding-post 8. If now the current over the line should be in excess of the requirements, the bars 7 11, being of such metal 70 as to carry the predetermined load, will heat up and expand, thus causing them to move upwardly at their jointed ends, carrying therewith the link 16 and causing the end of the lever 13 to move downwardly, cutting out the 75 electric circuit through the plate 25 and throw- ing in the resistance-coil 23. Should the current increase and the bars still further expand, it is desirable that the bars 7 11 should be cut out of the circuit, and by reference to 80 Fig. 1 it will be seen that when the contact-face 21 of the lever 13 has reached the third contact-post of the resistance-coil the other end 15 of the lever has moved from the plate 18 to plate 17, as shown by dotted lines 27, 85 thus breaking the circuit through the bars and diverting it entirely through the resist- ance-coils.

It is desirable that the resistance of the bars 7 11 should be approximately equal to the re- 90 sistance in the coils 23 up to the point where the bars are eventually cut out of the circuit.

It is obvious that when the contact-face 21 has passed over all the posts 22 the circuit will be broken and reestablished automatic- 95 ally by the contracting of the bars 7 11.

The expansion-bars are very sensitive, and it is found that the current will at times heat them up so rapidly as to carry the contact-face 21 of the lever 13 down to the lower con- tact 22 or beyond, so that temporarily in such cases the current is cut out entirely.

The object in cutting out the expansion-bars 7 11 as soon as the contact 21 has passed

the second contact 22 is to permit the bars to cool off, and thus permit them to contract and reëstablish the current therethrough.

What I claim as new is—

- 5 1. A cut-out for electric circuits comprising a pair of bars in an electric circuit, jointed together centrally and out of alinement with each other, a resistance-coil and means between said bars and resistance-coil for cutting the bars out of the circuit and diverting the current to the resistance-coil.
- 15 2. A cut-out for electric circuits, comprising a pair of bars in an electric circuit, jointed together centrally and out of alinement with each other, a resistance-coil, normally out of the circuit, and means between said bars and resistance-coil for temporarily diverting the current from said bars to the resistance-coils, and for entirely cutting out the current from 20 said bars, substantially as set forth.
- 20 3. A cut-out for electric circuits comprising a base, with a binding-post at each end, a

pair of bars centrally jointed and slightly out of alinement with each other, secured to the base and electrically connected at one end with the positive binding-post, the opposite end of said bars having electrical connection with a contact-plate on the base, a swinging lever, connected with the jointed bars, and operatively in engagement with the contact-plate on the base, and an adjoining contact-plate on the base connected up with the main circuit, and operatively brought into contact with the swinging lever, a resistance-coil in engagement with the swinging lever, and 35 electrical connection between the resistance-coil and the negative binding-post, as set forth.

In testimony whereof I affix my signature in presence of two witnesses.
